UNITED STATES PATENT OFFICE.

HARVEY B. BLACK, OF BOGOTA, NEW JERSEY.

STEAM-BOILER.

1,175,223.

Specification of Letters Patent. Patented Mar. 14, 1916.

Application filed December 27, 1912. Serial No. 738,796.

To all whom it may concern:

Be it known that I, HARVEY B. BLACK, a citizen of the United States, residing at Bogota, in the county of Bergen and State 5 of New Jersey, have invented certain new and useful Improvements in Steam-Boilers, of which the following is a full, true, and complete specification.

This invention comprises a steam boiler 10 furnace of the variety having a boiler shell, depending water legs or headers, and a nest of water tubes connecting the water legs and located above the grate, the furnace gases passing between and around the water 15 tubes on their way to the stack.

The object of the invention is to construct and combine the elements of the boiler and furnace so as to provide an improved course for the furnace gases from the fire-box 20 through the combustion chamber filled with water tubes. The flow of the gases is controlled and directed by means of baffles of such construction, and supported on the water tubes in such manner, as to render 25 them easy of application, adjustment and repair.

In the accompanying drawings illustrating the invention: Figure 1 is a vertical transverse section, parts being illustrated 30 conventionally; and Fig. 2 is a side elevation, parts being broken away and omitted.

The boiler comprises a shell or drum 10 disposed longitudinally at the top of the boiler setting, depending front and rear 35 water legs 11 and 12, of any suitable construction, and water tubes 13 connecting the water legs. The combustion chamber containing the tubes 13 is bounded at front and back by the water legs 11 and 12, and at the 40 sides by the side walls of the furnace setting. The grate 20 extends across the furnace, below the combustion chamber, and may be of any suitable construction. For simplicity it is indicated diagrammatically. As shown in 45 Fig. 2 there may be two grates arranged end to end or back to back, their adjacent portions being supported on an abutment 14, and each grate being provided with a fire door at 15.

50 Horizontal lagging plates 16 are supported on top of the lower water tubes over the side portions of the grate or grates, so as to form horizontal baffle walls which extend from water leg to water leg and inward 55 from opposite sides of the furnace for a distance toward the center. These baffles re-

strict the up-flow of the furnace gases from the burning charge, and thus concentrate their action upon the central group of water tubes. Other lagging plates 17, having 60 their upper portions curved or hooked, are hung one above the other in overlapping relation on the side members of this central group of water tubes and thus form two inner spaced baffles which extend between 65 the water legs and from the inner edges of the horizontal baffles upward toward, but not to, the shell 10. The lagging baffles 17 thus constitute the side walls of an up-draft flue disposed directly over the central portion 70 of the grate and extending from end to end of the combustion chamber. This flue, together with the space over the grate below the horizontal lagging baffles 16, form in effect an inverted T-shaped primary combustion chamber. The shell 10 extends longitudinally over the open top of the central flue, and its under side is exposed to the action of the gases as they flow upward in the flue and reverse to move downward at 80 the sides.

All of the furnace gases flow upward in the central flue, impinge against the under side of the shell 10, and divide into two streams which flow downward at opposite sides of 85 the central flue, between and around more of the water tubes, and thence upward at the outer sides over the remainder of the tubes. In order to direct the flow of these two streams in the spaces at opposite sides 90 of the central flue and over the grate, but separated from the latter by the horizontal lagging 16, outer baffles 18, similar to the baffles 17, are provided. At the bottom these baffles terminate short of the horizontal 95 baffles 16 and at the top they are extended to meet the sides of the shell 10. The space between the sides of the shell and the hooked baffles 18, which are supported on the uppermost tubes, is bridged by suitable plates 100 18^b. The down-draft and up-draft flues thus formed at opposite sides of the central flue are of relatively small cross-sectional area, preferably less than half the area of the central flue, in order to preserve the velocity of flow by compensating for the decreased bulk of the gases due to cooling. The upper portions of the outer baffles are inclined upward and inward relatively to the lower portions, which may be substantially vertical, and the sectional character of the lagging enables me to employ longer 105 110

- plates 18^a at the bend, so that these plates project sidewise beyond the lower plates and thus restrict the exit from the outside up-draft flues. The horizontal plates 16 are 5 provided on top with channeled recesses, which channels in the innermost plates receive the lower edges of the bottom plates 17 to secure a lap joint at this junction. It will thus be observed that the flame and 10 gases from the burning charge are collected and caused to flow up in a single body over the central group of tubes; that the flow is divided at the top of the central flue into two streams, which are directed 15 versely in the side flues, passing over the remainder of the tubes and finally escaping into the space 19 at the top and sides of the boiler casing, whence they are allowed to escape to the stack in any suitable manner.
- 20 I claim:
1. In a boiler furnace, the combination of a grate, a boiler drum, downward-extending water legs at opposite ends of said drum, water tubes connecting said water legs, central spaced baffles supported on and parallel with the water tubes and extending upward toward said drum so as to form a central up-draft flue extending between the water legs directly over the central portion of the 25 grate, said drum forming the top of said flue, substantially horizontal baffles supported on the lower side water tubes and co-operating with the aforesaid baffles to separate the spaces at the sides of said central flue 30 from the grate, and baffles in said spaces supported on and parallel with the water tubes therein and dividing said spaces into down-draft and up-draft flues of relatively small area, all the furnace gases flowing up 35 in the central flue to the drum and thence dividing and passing downward and upward through the side flues.
  2. In a boiler furnace, the combination with a boiler drum, downward-extending water legs at the ends thereof, and water-tubes connecting said water legs, of lagging plates supported on said water tubes and forming baffles constituting the side walls of a central up-draft flue beneath said drum, 45 which drum extends longitudinally of the top of the flue exposed to the upward flow of combustion gases therein, other lagging plates supported on the water tubes and
- forming baffles at opposite sides of the aforesaid baffles, these side baffles extending 55 downward from the sides of said drum and constituting the division walls between down-draft and up-draft flues which communicate with the top of said central flue, and horizontal baffle plates supported on 60 the lower side water tubes and forming baffles extending from the sides of the furnace to the lower edges of the side baffles.
3. In a boiler furnace, the combination with a boiler drum, downward-extending 65 water legs at the ends thereof, and water tubes connecting said water legs, of inner baffles supported on the water tubes and extending between the water legs and upward toward said drum to form a central up-draft 70 flue filled with tubes, the drum forming the top of this flue, outer baffles supported on the water tubes meeting the sides of said drum and extending downward in the spaces at the sides of the central flue to separate 75 said spaces into down-draft and up-draft flues, connected with the top of the central flue, and substantially horizontal baffles supported on the lower water-tubes at opposite sides of the bottom of the central flue and 80 forming the bottom walls of the side flues.
4. In a boiler furnace, the combination with a boiler drum, water legs at the ends thereof, and water tubes connecting said water legs, of inner baffles extending between 85 said water legs and upward toward but not to said drum, outer baffles the upper portions of which are inclined inward with reference to the lower portions and meet the sides of said drum, and bottom baffles extending from the lower edges of the inner baffles across below the lower edges of the outer baffles, said baffles forming a central up-draft flue extending upward to the drum and side down-draft and up-draft flues 95 which divide the combustion gases from the central flue into two streams, said flues containing the water tubes.
- In testimony whereof, I have signed this specification in the presence of two witnesses. 100
